TOP POST AND CONNECTION

Filed Jan. 24, 1931

UNITED STATES PATENT OFFICE

1,950,742

TOP POST AND CONNECTION

Jules A. Olivier, Detroit, Mich., assignor to Dietrich, Incorporated, a corporation of Michigan

Application January 24, 1931, Serial No. 510,858

7 Claims. (Cl. 296—45)

As may be inferred from the above title, the present invention relates to means for the adequate support of a collapsible vehicle top,—such as may be used upon a convertible touring car, 5 or the like; and the invention relates specifically to a novel intermediate post, adapted to be secured at the top of a hinge post for oppositely swung doors and either to be disposed in an erect position of use or to be inwardly folded into 10 a position of disuse.

It is a primary object of the present invention to provide a novel and advantageous type of hinged connection including a special latch organization: and, in preferred embodiments of the 15 invention, the mentioned special connection, whether or not used upon a top-supporting post with which windows in car doors may cooperate, may include (in addition to a plate attached to the mentioned hinge post and provided with a 20 slidably adjustable latching element movable by manual means, and in addition to a cooperating plate secured at the "lower" end of the mentioned movable post and provided with a keeper and compressible cushioning means), special 25 webs respectively integral with said plates and interconnected by means comprising a horizontal but angularly disposed pivot pin.

Other objects of the present invention, including preferred details of construction of internal 30 or external threaded adjusting means for the mentioned slidable latching element or its keeper, and including other preferred details of construction of co-operating parts, may be best appreciated from the following description of one 35 illustrative embodiment of the invention, taken in connection with the appended claims and accompanying drawing.

Fig. 1 is a side elevational view of a car provided with a collapsible top in connection with 40 which an embodiment of the present invention is employed.

Figs. 2 and 3 are respectively sectional views, on a larger scale, taken substantially as indicated by the line 2—2 of Fig. 1, the former being taken 45 with the supporting post up, and the latter being taken with the supporting post folded down into an out-of-the-way position of disuse.

Fig. 4 is a detail elevational view, taken substantially as indicated by the arrow 4 of Fig. 3.

Fig. 5 is a vertical sectional detail view, taken substantially as is indicated by the lines 5—5 of Figs. 1 and 2.

Referring first to general features of the car and top organization illustrated in Fig. 1,—between a cowl section C and a rear body section S are shown doors D and D'; between these is disposed a fixed, upwardly extending body member in the form of a hinge post P; and a top T, extending over most of the mentioned parts and collapsible into a folded position above the rear sec-

tion S is shown as including, in addition to a rearward section R and a forward section F, a main intermediate bow B. The illustrated forward section comprises a transverse structural element E engageable with a windshield W, a subsidiary bow B', and a pair of horizontal members H. These horizontal members are preferably formed in three sections, in the general manner illustrated in detail in my co-pending application, Serial No. 523,401 filed Mar. 18, 1931; 65 but the exact character and mode of connection thereof with a removable intermediate post P' should be understood to be of subordinate interest herein. Preferred details of the construction and of the connection and cooperation of this 70 post P' with the mentioned post P and with additional parts constitutes the subject matter of the present application.

Referring now more particularly to details shown in Figs. 2—5 inclusive, the top of the post P and the lower end of the post P' are shown as provided with cooperating plates 10 and 11, respectively integral with inwardly extending webs 12 and 13,—the latter being pivotally interconnected by means comprising a substantially horizontal pin 14. This is outwardly inclined at the rearward end thereof,—the webs 12 and 13 being so offset at their inner ends, in a rearward direction, as to permit the post P' to be swung, when not in use, into an out-of-the-way position such 75 as that suggested by the dotted lines P'' in Fig. 1.

When it is in use, the upper end of post P' may be secured (preferably opposite the ends of bow B' of the horizontal frame member H, or its equivalent) by means such as a locking device 95 comprising a handle 15. This handle may be integral with a short vertical shaft 16 carrying a locking lug 17,—engageable beneath a plate 18 at the top of said post; but the connection here referred to may be established only after an outward pressure has been applied to the post P', sufficient to compress a cushioning element 19, carried by one of the plates 10, 11 and engaging the other of said plates, and after said plates have been secured in the opposing and parallel 100 relationship illustrated in Fig. 5, as by means of a special latch organization.

The post P' is shown as comprising both a wooden element and a metallic element, the latter being preferably integral with plate 11; and although various latching means might be employed releasably but very firmly to retain the post member P' in a substantially upright position above part P, or its equivalent, the plate 11 is herein shown as provided with an integral keeper element 20, projecting inwardly to a level slightly below the main plane thereof; and the plate 10 is herein shown as provided with a cylindrical chamber 21, through which extends the body of a wing screw 22,—said screw being pro- 110 115 120

vided with means such as a round-pointed screw 23, entering a peripheral groove 24 therein, to prevent longitudinal movement thereof although permitting a rotative movement such as slidably 5 to advance or retract a latch element 25. The latter is shown as received in a horizontal slot 26 in plate 10 and as engageable with the mentioned keeper 20.

The general mode of use of all parts referred to 10 having been indicated in connection with the description thereof, it will be understood that whenever a top of the general character illustrated, or any preferred top, is to be or has been collapsed, or even when the port P' is merely to be dispensed with by reason of the fact that windows slidable 15 in the doors D, D' and in guides (not shown) on post P' are to be left in positions of disuse, the post P' may be swung downward in the indicated manner; and, if desired, the web 13 may include 20 an extension providing a stop face 26 for engagement with a corresponding stop surface 27, provided upon web 12; but it should be understood that these last-mentioned features, as also the method of securing the top of the post P' in its 25 position of use, are relatively immaterial to the present invention. In its dependent position the posts P' may fit into corners behind the ends of a seat (not shown) in proximity to the posts P.

In conclusion, it should be understood not only 30 that various features of the described invention might be independently employed but also that numerous modifications, additional to any suggested herein, might easily be devised by skilled workers, if informed of the foregoing,—all without departure from the scope of the present invention, as the latter is indicated above and in 35 the following claims.

For example, although the fixed and rugged character of the post P suggests that it, rather 40 than movable post P', proportioned to interfit below top T, carry some latch element such as that movably secured within the plate 10 of the former, it will be obvious that the illustrated 45 relationships might be reversed, and that other rattle-obviating cam latch means than those shown might be provided upon or within either of said posts.

It is, however, found highly desirable to dispose 50 any resilient element, such as cushion 19, between the ends of aligned supporting posts P and P'. This construction adapts the post P' to be firmly grasped, in the manner of a lever fulcrumed on pin 14, to compress said resilient element in a manner which facilitates easy adjustment of the latch element 25; and the 55 easy and indefinite adjustability of this latch element renders the new organization very positive and greatly superior to known organizations using spring catches or thimb-operated open links, or like devices subject to deterioration, in the securing of top-supporting posts P', or the like.

What I claim is:

1. In an automotive vehicle comprising an upwardly extending body member: a movable post member; securing means therefor including plates respectively carried by said body member and said post member, cooperating parts carried by said plates for releasably holding said post 70 member in an upright position upon said body member, cooperating inwardly extending webs, integral with said plates respectively, and a pivotal joint arranged between said plates for piv-

otally guiding said movable post member from an abutting position in extension of said body member to a position laterally of and substantially parallel to said body member.

2. In an automotive vehicle comprising an upwardly extending body member: a movable post member; and securing means therefor including plates respectively carried by said body member and said post member,—said plates being provided with cooperating parts releasably holding said post member in an upright position upon said body member and with interconnecting means comprising cooperating inwardly extending webs, integral with said plates respectively, and a pivotal joint, between said plates, comprising a pin disposed in a horizontal plane and outwardly inclined at the rearward end thereof.

3. In an automotive vehicle comprising an upwardly extending body member: a movable post member; and securing means therefor including plates respectively carried by said body member and said post member, cooperating parts carried by said plates for releasably holding said post member in an upright position upon said body member, and angularly offset interconnecting means for said plates so disposed as to permit said post to swing to an out-of-the-way dependent position substantially parallel to the adjacent portion of said body member.

4. In an automotive vehicle comprising an upwardly extending body member: a movable post member; and securing means therefor including plates respectively carried by said body member and said post member, said plates being provided with cooperating parts releasably holding said post member in an upright position upon said body member and comprising a latch element associated with one of said members and a keeper element associated with the other of said members, one of said last-mentioned holding elements 115 being provided with threaded means for a slideable adjustment thereof.

5. In an automotive vehicle comprising an upwardly extending body member: a movable post member; and securing means therefor comprising a latch element associated with one of said members and a keeper element associated with the other of said members, said members being provided with cushioning means between adjacent ends thereof.

6. In an automotive vehicle comprising an upwardly extending body member: a movable post member; and securing means therefor comprising a latch element associated with one of said members and a keeper element associated with the other of said members, said members being provided with cushioning means between adjacent ends thereof, said latch element being adjustable, and said posts being so pivotally interconnected as to adapt said movable post member to serve as a lever for the compression of said cushioning means during a tightening of said latch element.

7. A post for the body of an automotive vehicle comprising a pair of parts, one part foldable to a position laterally of and substantially parallel to the other part, a hinge connecting said parts and comprising two laterally extending web portions, a portion interconnected to form a pivot, and co-operating latching elements 145 provided in each of said web portions for locking the portions when together.

JULES A. OLIVIER.
